Primary Examiner — Selina Sikder(74) *Attorney, Agent, or Firm* — ScienBiziP, P.C.(57) **CLAIM**

The ornamental design for a power controller, as shown and described.

DESCRIPTION

FIG. 1 is a top, front, right side perspective view of a power controller, showing my design.

FIG. 2 is a bottom, rear, left side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The details shown in broken lines form no part of the claimed design.

1 Claim, 8 Drawing Sheets(56)
